DEVICE FOR APPLYING A COATING TO FABRIC

Filed Nov. 27, 1937

A technical drawing of a rectangular frame. Inside the frame, there are two vertical columns of short, vertical tick marks. The left column is labeled '20' at its base. The right column is labeled '19' at its base. Above the right column, the label '18' is positioned with an arrow pointing to the top of the column. At the bottom of the frame, the label '10' is centered. To the right of the frame, the label '15' is positioned with an arrow pointing to the right edge of the frame. Above the frame, the label '8' is positioned with an arrow pointing to the top edge of the frame. The entire drawing is enclosed in a rectangular border.

DEVICE FOR APPLYING A COATING TO
FABRIC

Maxwell H. Bloomberg, Brighton, Mass.

Application November 27, 1937, Serial No. 176,868

2 Claims. (Cl. 91—25)

This invention relates broadly to devices for applying a coating to strips, particularly strips of fabric; and the present invention is particularly designed for applying plaster of Paris, in powdered form, to strips of bandage, and more particularly to gauze, in roll form, and as generally used for bandages.

An object of the invention is to provide a device whereby plaster of Paris may be applied to rolled bandages in a quick, positive and efficient manner.

The invention together with its objects and advantages will be best understood from a study of the following description taken in connection with the accompanying drawing wherein:

Figure 1 is a longitudinal sectional view through the device,

Figure 2 is a top plan view thereof, and

Figures 3 and 4 are vertical transverse sectional views taken substantially on the lines 3—3 and 4—4 of Figure 1.

Referring to the drawing by reference numerals it will be seen that the device, in the preferred embodiment thereof, is preferably formed of metal and comprises a substantially rectangular relatively shallow pan or receptacle 5 having a bottom wall 6, side walls 7, and end walls 8 and 9.

At one end thereof the bottom wall 6 is extended beyond the wall 8 of the pan as at 10 to provide a platform from which the coated bandage feeds to be rolled on a shaft 11.

Shaft 11 is rotatably supported between a pair of posts 12 that rise from a foot piece 13 integral with the bottom extension 10 of the pan through the medium of a perpendicular flange or web 14.

The foot 13 and flange 14 provide a support for the forward end of the device while the rear end of the device is supported by a substantially U-shaped stand 15 the sides of which at their upper ends are suitably secured to or otherwise made integral with the bottom 6 of the pan at the end 9 of the pan.

To accommodate the bandage strip 16 walls 8 and 9 at the lower edges thereof are provided with slots 17 and 18 respectively.

The sides 7 of the pan at the end 9 thereof are extended beyond said end of the pan as at 19 and said side extensions 19 are suitably apertured to accommodate a rod or shaft 20 on which the bandage roll 16 is supported so that with the strip of bandage trained over the bottom 6 of the pan and through the slots 18 and 17 the bandage

will feed from the roll 16 onto the shaft 11, passing through the pan 5.

The pan 5 is adapted to contain to a suitable level the powdered material 21, in the present instance plaster of Paris.

For the most part thereof the powdered material 21 is confined in the pan between the wall 9 thereof and a transversely disposed brush 22.

Brush 22 is of the bristle type and embodies a head 23 which at its opposite ends is provided with outstanding lateral flanges 24. The flanges 24 are provided with vertical rows of apertures 25 for selective alignment with apertures in the sides 7 of the pan whereby to accommodate pins 26 through the medium of which the brush 22 is secured at the desired vertical position of adjustment with the bristles in wiping contact with the bandage strip 16 as the latter feeds through the pan 5.

The brush 22 will serve to work the powdered plaster of Paris material into the gauze or fabric 16.

For catching any loose powder falling from the gauze 16 as it winds into a roll on the shaft 11 there is provided a pan 28 which is of such dimension as to accommodate therein the foot 13 as clearly shown in the drawing.

It will thus be seen that with a device of this character plaster of Paris, in powdered form, may be readily and quickly applied to rolled bandages.

It is thought that a clear understanding of the construction, utility and advantages of an invention of this character will be had without a more detailed description.

Having thus described the invention what is claimed as new is:—

1. A device for applying plaster to a roll bandage comprising a pan including a bottom wall, a pair of side walls and a pair of end walls, said end walls having slots in their lower ends, and said side walls at one end of the pan projecting beyond the adjacent end wall, a transverse member supported by said side wall extensions for supporting a bandage roll, a brush supported in the pan adjacent the other end wall, the plaster being placed in the pan between the brush and the first-mentioned end wall and on that portion of the strip of bandage which passes between the first-mentioned end wall and the brush, said bottom wall having a platform forming extensions at its rear end for forming a rest for a portion of the strip after the same is passed through the pan, a depending flange at the rear end of the bottom wall of the platform, a horizontal foot portion connected with the lower edge of

- the flange, uprights on said foot portion, a shaft journalized in the uprights for receiving an end of the treated strip, a small receptacle in which the foot portion rests and a leg member depending from the front end of the pan.
5. 2. A device for applying plaster to a roll bandage comprising a pan including a bottom wall, a pair of side walls and a pair of end walls, said end walls having slots in their lower ends, and said side walls at one end of the pan projecting beyond the adjacent end wall, a transverse member supported by said side wall extensions for supporting a bandage roll, a brush supported in the pan adjacent the other end wall, the plaster being placed in the pan between the brush and the first-mentioned end wall and on that portion
- 10 of the strip of bandage which passes between the first-mentioned end wall and the brush, said bottom wall having a platform forming extension at its rear end for forming a rest for a portion of the strip after the same is passed through the pan, a depending flange at the rear end of the bottom wall of the platform, a horizontal foot portion connected with the lower edge of the flange, uprights on said foot portion, a shaft journalized in the uprights for receiving an end of the treated strip, a small receptacle in which the foot portion rests and a leg member depending from the front end of the pan, and means for adjusting the brush vertically in the pan.
